AMPLIFIER GAS TUBE

William Merle Webster, Jr., Princeton, N. J., assignor to Radio Corporation of America, a corporation of Delaware

Application November 22, 1950, Serial No. 197,014

7 Claims. (Cl. 313—189)

1

This invention relates to improvements in gas tubes which are suitable for use as amplifiers in that they have continuous grid control. More particularly it relates to amplifier gas tubes of a particular kind having very high values of transconductance and of anode current, and extremely low values of output impedance which are described in the co-pending application assigned to the same assignee as the present application, Serial No. 185,745, filed September 20, 1950 (RCA 33802).

Tubes of this kind have offered very great advantages over the tubes which preceded them. However, they also have certain limitations which will best be understood by first reviewing their basic operating principles. In any such tube there are separate discharge paths for the load current and the ionizing current. During operation the energizing potential required for drawing load current, from a main cathode to a main anode, is always below the value required to produce ionization. However, a separate ionizing electron discharge, "an auxiliary discharge," is energized with a higher potential to assure ionization. It ionizes the gaseous filling of the tube creating a conductive "plasma" by converting neutral gas atoms into positive ions and detached, free, negative electrons. The plasma surrounds the main cathode and fills the load current discharge path. As a result the electron space charge surrounding the cathode is neutralized by positive ions and the plasma effectively acts as a low impedance conductor connected between the cathode and the anode.

Since the auxiliary discharge is energized with a steady direct potential the plasma density will remain constant. Moreover, neither the voltage variations of the signal applied to the control electrode, in its location in the load current discharge path, nor the corresponding variations of low-velocity load current discharge are effective to change the constant density of the plasma. Thus the plasma influences only the magnitude of the direct current component of the load current.

The load current in a tube of this kind may easily be hundreds of times greater than the auxiliary discharge current upon which it depends.

Because of the fact that the load current electron discharge from the main cathode to the main anode is incapable of producing ionization, a control grid located between these electrodes is able to retain control even though it is entirely immersed in the plasma. This was a great ad-

vantage over previous gas tubes in which the path of the ionizing discharge always coincided with that of the load current discharge, and therefore extended with it through the control grid opening(s), with the result that the grid was deprived of any further ability to control the anode current once the gaseous filling of the tube became ionized. The mechanics of why the negatively biased control grid can vary the load current is that as the input signal varies the instantaneous negative potential of the grid a positive ion sheath which surrounds it varies in thickness and this varies the cross-sectional areas of the columns of plasma which extend thru its openings.

Two limitations of tubes of this kind have been: that the grid-voltage versus plate-current characteristics have usually been somewhat non-linear and that the attainable transconductances are rather limited due to the fact that the grid must be capable of directly controlling a very large magnitude current.

It is the object of the present invention to devise a gas amplifier tube of the kind in question with a grid-voltage versus plate-current characteristic of improved linearity.

It is a further object of the present invention to provide gas tube amplifiers of the kind in question of even greater values of transconductance.

These objects have been obtained by making certain modifications of the tubes mentioned above.

According to the principal modification of the present invention the control grid is located in a different position where it will be able to control the magnitude of the auxiliary electron discharge rather than to directly control that of the load current electron discharge. The purpose in so doing is to indirectly effect control of the load current by varying the density of the plasma. Since the rate at which the density of the plasma can diminish is a function of deionization time, and therefore, is limited, this type of control results in lowering the upper limit of the frequency range of operation. However, more linear eg/ip characteristics result from this kind of control while at the same time the attainable upper frequency limit is still high enough for many applications such as audio use. In addition, since direct control of the relatively small ionizing current results in indirect control of the very large load current the attainable transconductances benefit from a multiplication effect analogous to that obtained in secondary

emission electron multiplier tubes. Extremely large transconductances, such as transconductances of the order of one or more mhos, have been attained.

In the drawing:

Figure 1 represents a longitudinal sectional view of an illustrative embodiment. The section is taken along line 1—1 of Figure 2 and in a plane which is parallel to the axes of the cylindrical cathodes;

Figure 2 represents another longitudinal sectional view of this embodiment, this section being taken along the line 2—2 of Figure 1 and in a plane perpendicular to that of the section of Figure 1; and

Figure 3 is a schematic circuit diagram of an audio amplifier system using the gas tube shown in Figs. 1 and 2.

The gas tube 10 shown in Figs. 1 and 2 comprises a gas-tight envelope 11 which, in this illustrative embodiment, is of substantially rectangular shape. The load current in this tube originates at a main source of electrons, consisting of two indirectly heated cathodes 12, 13, and flows to a main anode 14 and an accelerating grid 15. An auxiliary cathode 16 serves as a source of electrons for the ionizing discharge. According to the present invention the ionizing electron current is amplitude modulated. To this end the auxiliary cathode 16 is arranged with a number of other electrodes to constitute what may be called an auxiliary triode. These elements are a control grid 17, which in the example herein is constructed in the same manner as semi-cylindrical half of a bird cage grid; a slotted anode 18; and a shield 19. In the operation of this tube the anode 18 draws electrons from the auxiliary cathode 16 and those which emerge from its slot 20 are then attracted into the region of the main load-current paths of the tube.

The anode 14 and the shield 19 are supported on rods 21 and 22, respectively, which are sealed through the opposite ends of the envelope 11 to serve as terminal pins and support rods. The grid 17 is supported on a pair of wires 23, 24 the latter of which extends through the bottom of envelope 11 to serve as a terminal pin. The main and auxiliary cathodes are supported by wires which are fused through the top of envelope 11, such as wires 25, 26, 27 and 28, respectively, which appear in Figure 1. In accordance with the usual practice, one of each of these pairs of wires serves as a terminal pin for the cathode sleeve as well as for one side of the heater thereof, while the other serves as the terminal pin for the opposite side of the heater. The slotted anode 18 as well as the accelerating grid 15 and a screen grid 29 are supported between the top and bottom of envelope 11 as shown in Figure 1. Suitable ones of the support wires used for this purpose extend through the bottom of the envelope to provide a respective terminal pin for each of these elements.

In order not to include unnecessary detail in the drawing, and because the cathodes may be of any of a number of suitable types known in the art, none of the cathodes is shown in section. In general, indirectly heated types of cathodes (particularly for main cathodes) are to be preferred for a number of reasons, e. g., their greater rigidity (than filamentary cathodes) and the resultant freedom from microphonics; the reduced likelihood of hum when A.-C. heater current is

used; and the more copious emission of electrons.

Each of the improved tubes shown herein may be processed in any of a number of ways well known in the art to provide a gaseous filling G within its envelope prior to sealing off. Any suitable gas or mixture of gases may be utilized. The gas pressure for a particular pick-up will be in accordance with its specific electrode geometry and spacings and must be such as to favor the formation of a self-sustaining ionizing discharge. A number of gas tubes of the kinds employed in the present pick-ups have been found to operate satisfactorily with a filling of helium at a pressure of approximately 750 microns. However, as is well known other gases and other pressures may be used, e. g., gas pressures which lie within the range between approximately 100 microns and several millimeters of mercury.

Figure 3 shows a circuit which is suitable for using the gas tube shown in Figures 1 and 2. In the operation of the tube the potential of the slotted anode 18 is positive with respect to auxiliary cathode 16 but not sufficiently so to produce ionization between them.

Some of the electrons which are attracted from the auxiliary cathode 16 toward the slotted anode 18 will drift through the slot 20 and toward a group of electrodes including those which carry the useful load currents. Since the "auxiliary triode" is operated with such a low anode potential it will behave like a vacuum tube rather than a gas tube. That is to say it will be possible to use its grid to effect plate current variations in a substantially linear fashion over a usefully large range. Referring again to Figure 3, two separate direct current potential sources are shown, a low potential source 30 and a high potential source 31. The source 30 is used for maintaining the small potential difference between the main source of electrons, the pair of cathodes 12, 13, and the load current collecting electrodes, the accelerating screen 15 and the main anode 14. The source 30 may consist of a number of series-parallel-connected 1½ v. dry cells, a storage battery, or any similar fairly-high current source. This is because it must serve not merely for establishing a bias but also for delivering to the utilization device 37 a signal-bearing current having an average value of the order of one or several amperes. Conversely the source 31 should be capable of providing a relatively much higher potential but it need not be capable of providing large continuous currents. It serves primarily as the energizing source for the ionizing discharge and in addition it provides a number of bias potentials. The source 31 comprises a battery 32, providing a potential well in excess of that required to ionize the gaseous filling of the tube 10, and a voltage divider 33 having a number of movable taps. A ground connection 34 is at such a point in source 31 that it provides a negative bias potential for the grid 17 as well as a number of adjustable positive potentials. The grid 17 is biased for class A operation and an input signal from a source 35 is algebraically added to the bias by some appropriate means such as the transformer 36 shown herein.

The entire group of low current carrying electrodes, i. e., the two main cathodes 12, 13, the anode 14, and the accelerating grid 15 may be considered as a composite final accelerating anode for the ionizing discharge. Accordingly, this entire group of electrodes is polarized at a rela-

tively high potential as shown in Figure 3. The screen 29 is polarized at a potential intermediate that of a slotted anode and the auxiliary cathode. The reason for selection of such potentials will be understood from the description which follows.

For proper operation of the tube 10 it is desirable to prevent or inhibit any tendency of positive ions to drift from the right hand region of the tube back through the slot 20 into the inter-electrode spaces of the auxiliary triode where their presence would tend to impair its proper operation. Accordingly, means are provided herein for trapping positive ions in two low potential troughs from which it will be difficult for them to escape so as to be free to move toward the triode section. A first low potential trough may be established just beyond the slotted anode 18 by properly polarizing the screen 29. In the operation of this device, this screen is maintained at a potential above that of the auxiliary cathode 16 but below that of the slotted anode 18. As a result the electrons which, as explained above, will emerge from the slot 20 at velocities too low to produce ionization, will be retarded by the screen 29 (but not stopped) so as to emerge from its right hand side at even lower velocities. The next element in the path of these electrons is the accelerating grid 15. In the normal operation of tube 10, this electrode is maintained at a potential somewhat above the ionizing potential of its gaseous filling G. In this arrangement it is to be expected that at least some of the electrons approaching the accelerating grid 15 will have ionizing collisions slightly before they reach it and that for this reason positive ions will be present to the left of this element (as it appears in the drawing). However, any leftward movement of these ions will be limited as most of them will be attracted into and trapped within the low potential trough of the screen 29. Of course, the inertia of some of these ions will be sufficient so as to tend to carry them all the way up the left slope of the potential trough. However, a large percentage of these will lose much of their inertia in collision with gas atoms. Moreover, most of those which do get up the left slope will collide with solid portions of the slotted anode 18 so that only a very few will ever pass through its slot 20. The slower ions will oscillate leftward and rightward through the screen 29 thereby remaining trapped in the trough which it establishes and eventually they will be collected by this element and neutralized. Most of the ionizing collisions will occur in a second low potential trough to the right of the accelerating grid 15 in which, therefore, a dense plasma will be established. It is in this region that the main source of thermally emitted electrons is located. This source in the present example is a pair of indirectly heated cathodes 12, 13. The main anode 14 is mounted to the right of these cathodes. It may be polarized at the same potential as the accelerating grid 15 while the two cathodes 12, 13 are polarized at a potential a few volts below it, i. e., below the common potential for these two load-current-collecting elements. It is in this way that the second low potential trough is established between the accelerating grid 15 and the main anode 14 and it is in this trough that the greatest number of positive ions will be trapped. During the operation of the tube the electron discharge current which issues from the slot 20 is modulated in accordance with the signal potential-variations of the grid 17.

In the preferred embodiment shown herein certain electrodes are common to both the load current and the auxiliary current discharge paths. These are the electrodes 12-15 which act as a composite anode for the auxiliary discharge. However, as shown in the above-mentioned co-pending application Serial Number 185,745, it is entirely possible to use a separate anode as a collector of the electrons forming the auxiliary discharge, e. g., to use a geometrical arrangement in which the main and auxiliary discharge paths cross each other. Even the use of side-by-side discharge paths will be feasible where the ionized gas is free to diffuse from the one to the other.

I claim:

1. A gas amplifier tube comprising: a sealed envelope containing a gaseous filling; said envelope further containing a main cathode and a main anode in cooperative spaced relationship at opposite ends of a load current path therein; a space charge limited cathode and an electrode for receiving electrons therefrom positioned within the envelope and surrounded by said gaseous filling at opposite ends of an auxiliary discharge path which does not coincide with said load current path but a portion of which is in close proximity thereto; terminals over which a source of ionizing potential may be connected between said auxiliary cathode and said receiving electrode for producing an ionizing discharge to provide a conductive plasma between said main cathode and anode; and a control grid adjacent said auxiliary cathode for controlling the ionizing discharge and thereby the plasma density.
2. A gas tube as in claim 1 which further comprises an electron-transparent electrode positioned in a region athwart said auxiliary discharge path on the far side of said grid from said auxiliary cathode; and a terminal over which a source of potential may be connected to said transparent electrode for trapping positive ions in said region to prevent them from entering the space between the auxiliary cathode and the control grid.
3. A gas tube comprising; a sealed envelope containing a gaseous filling; a group of load circuit electrodes within the envelope and including at least one main cathode and a main anode having, respectively, electron-emitting and electron receiving surfaces which define opposite ends of a predetermined load current path; means including a space charge limited auxiliary cathode and an electrode for collecting electrons therefrom surrounded by said gaseous filling and positioned in spaced-apart relationship for producing an ionizing discharge of electrons along a path within in said envelope which does not coincide for all of its length with all of said load current path but includes a portion in such close proximity thereto, for example, coincidental therewith or crosswise or adjacent thereto, that plasma produced by said ionizing discharge bathes the main cathode and extends over all of said current path; a control grid adjacent said auxiliary cathode for controlling the ionizing electron current; an electron-transparent electrode positioned in a region athwart said ionizing discharge path on the far side of said grid from said auxiliary cathode; and a terminal over which a source of ionizing potential may be connected to said transparent electrode for trapping positive ions in said region and preventing them from reaching the auxiliary cathode and the space between it and said control grid.

4. A gas tube as in claim 3 which further comprises a first accelerating electrode between said control grid and said transparent electrode for drawing electrons from the space charge of the auxiliary cathode to project them along the path of the ionizing discharge and thru the transparent electrode, and a post-accelerating electrode on the far side of said transparent electrode from the first accelerating electrode for accelerating the last-mentioned electrons to project them with ionizing velocities over said portion of the path of the ionizing discharge which is in proximity to the load current path.

5. A gas tube comprising; a sealed envelope containing a gaseous filling; a group of load circuit electrodes within the envelope and including at least one main cathode and a main anode having, respectively, electron-emitting and electron receiving surfaces which define opposite ends of a predetermined load current path; means including an auxiliary cathode and an electrode for receiving electrons therefrom surrounded by said gaseous filling and positioned in spaced relationship for producing an ionizing discharge of electrons along a path within said envelope which does not coincide for all of its length with all of said load current path but includes a portion in such close proximity thereto, for example, coincidental therewith or crosswise or adjacent thereto, that plasma produced by said ionizing discharge bathes the main cathode and extends over all of said load current path; a control grid adjacent said auxiliary cathode for controlling the ionizing electron current; a slotted anode on the far side of said grid from said auxiliary cathode for drawing electrons through the former from

the latter; and an electron-transparent electrode for producing a low potential trough athwart the path of the auxiliary discharge in a region between the slotted anode and said portion of the ionizing discharge path which is in close proximity to the load current path.

6. A gas tube as in claim 5 which further comprises an electron transparent post-accelerating electrode between said first mentioned transparent electrode and said portion of the discharge path in proximity to the load current path.

7. An electron discharge device inculding an envelope containing a gaseous atmosphere, a main cathode and a main anode within said envelope defining a load current path, a space charge limited auxiliary cathode outside said path for supplying electrons for ionizing the space between said main cathode and anode, said main cathode and anode being adapted to have a potential applied therebetween less than the ionizing potential, a grid adjacent said auxiliary cathode between it and said path, and an apertured electrode between said grid and path through which electrode electrons from said auxiliary cathode may be projected, said grid and apertured electrode being adapted to be maintained at less than ionizing potential with respect to said auxiliary cathode, and an accelerating electrode between said apertured electrode and said path for accelerating electrons from said auxiliary cathode to ionizing potential in a region near to said main cathode.
